UNITED STATES PATENT OFFICE.

JOHN S. BRENNAN, OF MILWAUKEE, WISCONSIN, ASSIGNOR TO A. J. LINDEMANN & HOVERSON CO., OF MILWAUKEE, WISCONSIN.

CONVERTIBLE FLUID-FUEL KINDLER AND HEATER FOR STOVES.

1,218,974.

Specification of Letters Patent.

Patented Mar. 13, 1917.

Application filed December 11, 1915. Serial No. 66,334.

To all whom it may concern:

Be it known that I, JOHN S. BRENNAN, a citizen of the United States, and resident of Milwaukee, in the county of Milwaukee and State of Wisconsin, have invented certain new and useful Improvements in Convertible Fluid-Fuel Kindlers and Heaters for Stoves; and I do hereby declare that the following is a full, clear, and exact description thereof.

This invention relates to new and useful improvements in stoves, particularly of that type which are adapted to utilize both solid and fluid fuel.

15 It is the primary object of the invention to provide a means whereby the usual water container in the fire box may be heated either by solid fuel on the grate, or by fluid fuel, or if desired by both solid and fluid fuel to supply a great amount of heat to the said container for meeting unusual conditions of use of the hot water system associated therewith and to provide for an exceedingly rapid heating of such water.

25 It is further an object to utilize the fluid fuel heating means as a means for kindling solid fuel such as coal in the fire box of a stove whereby the starting of a fire is greatly facilitated and whereby the annoyance of the usual laborious method of kindling is obviated.

30 A still further object resides in the provision of a single burner member which is movable to direct its flame either toward the grate member of the fire box to kindle the solid fuel thereon, or toward the water container to heat it when there is not a solid fuel fire in the stove, whereby the fullest heating power of the burner may be utilized 40 in either of the operations.

With the above and other objects and advantages in view, the invention resides more particularly in the novel combination, arrangement and formation of parts more particularly hereinafter described and particularly pointed out in the appended claims.

Reference is had to the accompanying drawings wherein similar characters of reference designate corresponding parts throughout the several views and in which:

Figure 1 is a vertical sectional view

through the fire box of a stove equipped with the present invention, the sectional view being taken on the line 1—1 of Fig. 2.

Fig. 2 is a horizontal sectional view taken 55 through the fire box in a plane including the axis of the burner member, this view being on the line 2—2 of Fig. 1.

Fig. 3 is a vertical sectional view taken transversely through a fire box on the line 60 3—3 of Fig. 4, and illustrating a modified form of burner and water container.

Fig. 4 is a horizontal sectional view taken through a fire box on the line 4—4 of Fig. 3.

Fig. 5 is a detail sectional view on the line 65 5—5 of Fig. 4 showing the operating and indicating means of the burner.

Referring now more particularly to Figs. 1 and 2 of the accompanying drawings, there is shown the fire box portion of a 70 stove including the outer side wall 5 which is the outer wall of the stove, and the inner wall 6, the front wall of the stove and of the fire box being designated at 7. Disposed adjacent the walls 5 and 6 are the 75 usual grid members 8 which are inclined away from the walls toward their bottoms and below which is positioned the grate 9. Lying against the inner face of the grid member adjacent the wall 5 is a water container which includes series of pipes 10 which extend horizontally and form what is termed the water container and which are connected in any suitable manner to a water heating system, not shown, these pipes being 85 adapted to be normally heated by a coal or other solid fuel fire disposed on the grate 9.

The kindling and water heating burner comprises a pipe section 11 rotatably mounted in a bearing 11', provided on the rear 90 portion of the inner face of the wall 5 and in a bearing 12 carried by the wall 7 through which the pipe is passed, whereby the burner member extends horizontally between the grate 9 and the pipes 10 and may be rotated 95 to direct the flames issuing from a longitudinal series of jet openings 12 in its side, either toward the grate 9 or toward the water pipes 10. The rear end of the burner pipe is suitably closed, and the front end 100 which projects outwardly of the stove wall 7 carries an air mixing member 14 with

which is connected in the usual loose manner, the valved branch 15 of a suitable supply pipe.

For rotating the burner pipe to either 5 of its operative positions, an arm 16 extends laterally from its forward portion and is passed through a vertical slot 17 in the side wall 5, the free end of the arm being directed laterally and provided with a transverse 10 head 18, substantially square in cross section. The slot 17 is of such length that abutment of the arm 16 against either end thereof, determines the proper position of the burner for its respective operation, and 15 the position of the slot and arm is such relatively, that at either limit of movement of the arm, one of the flat faces of the head 18 is disposed substantially in a horizontal plane, and these faces carry symbols 19, 20 which indicate the operative position of the burner whereby a person looking downwardly on the head will be apprised of the operative position of the burner.

Taking up now the modified structure 25 shown in Figs. 3 to 5 of the drawings, there is shown a conventional fire box structure similar to the one heretofore described and wherein as in the previous structure 5 designates the outer side wall, 6 the inner side wall, 7 the front wall, and 9 the grate. 30 Adjacent the inner side wall 6 is the usual grate member 8, but adjacent the wall 5 is a tank member 8^a forming the water container, to thus dispense with the pipes 10 of the 35 previous structure. The bottom of this member 8^a, however, comprises a plurality of grid sections 8^b, the upper portion only being in the shape of a tank.

The burner member of the present structure 40 comprises a pipe 20 disposed longitudinally in the fire box between the member 8^b and the wall 5, and above the grate 9. The end of the pipe adjacent the back of the stove is closed by a cap 21 and is journaled 45 in a bearing 22 carried by the adjacent portion of the wall 5, and the front end of the pipe is extended outwardly of the stove through a bearing sleeve 22' carried in the front wall 7 and carries the usual air mixing member 23 with which is connected in the usual loose manner a valved supply pipe 24. The pipe is provided with spaced longitudinal slits 25 through which the gas escapes and is ignited in two sheets of flame 50 which are adapted to lie at the sides of and envelop either the water container or the grate according to whichever direction the pipe is turned as indicated in Fig. 3. When the pipe is turned for kindling fuel on the 55 grate, it is noted that one sheet of flame will directly engage with the fuel and the other sheet will pass under the grate and will engage with the fuel at a point more remote. For actuating the burner pipe to either de-

sired position, and for indicating the position of the pipe, the bearing sleeve 22' is provided on the outer face of the front wall 7 with a flange 26 which has its upper portion enlarged to form a symbol plate and carrying the symbols 27. A ring 28 is 70 clamped on the pipe outwardly of the flange 26 and this ring carries an indicating arm 29. The ring also serves to hold the pipe against displacement with respect to the bearing sleeve 22'.

Either of the forms of the invention described provides a simple and readily operated means for procuring the advantages set forth. As the burner in both instances is disposed above the grate 9 and outwardly of the fire chamber formed by the respective grate members 8, it does not in any manner interfere with the fire chamber. At the same time the burner is fully protected from the solid fuel fire due to its location, hence it 85 cannot be damaged by fire or clogged by ashes.

I claim:

1. In a fire box including a grate, a side grid member and a water container associated with the grid member, the combination of a fluid fuel burner apparatus permanently secured in the fire box juxtaposing the grid member, said apparatus being shiftable to adapt it for either kindling fuel on the grate or for heating water in the container.

2. In a fire box including a grate, a side grid member and a water container associated with the grid member, the combination of a fluid fuel burner permanently secured in the fire box and extending longitudinally thereof outside of the grid member, said burner being rotatably mounted to direct its flames toward either the grate or the water container, and means for rotating said burner.

3. In a fire box including a grate, a side grid member and a water container associated with the grid member, the combination of a permanently secured fluid fuel burner extending longitudinally of the fire box at one side thereof between the grate and grid member, the burner being rotatably mounted and provided with spaced longitudinally-extended series of fuel outlets adapted to direct flame at both sides of either the grate or the water container, and means for rotating said burner for selective association with the grate and said water container.

4. In a fire box provided with a front opening and having a grate, a side grid member, and a water container associated with the grid member, the combination of an indicator plate, a sleeve carried by the indicator plate and secured in the fire box opening, a burner pipe journaled in said sleeve, a journal bearing for the inner end of the burner pipe whereby it may be rotated

to direct its flames either toward the grate
for kindling fuel or toward the water con-
tainer, a split collar clamped on the pipe
outwardly of the plate and an indicator arm

5 carried by the collar.

In testimony that I claim the foregoing

I have hereunto set my hand at Milwaukee,
in the county of Milwaukee and State of
Wisconsin, in the presence of a witness.

JOHN S. BRENNAN.

Witness:

M. E. DOWNEY.
